UNITED STATES PATENT OFFICE.

JOHN HOULEHAN, OF EL PASO, TEXAS, ASSIGNOR, BY DIRECT AND MESNE ASSIGNMENTS, OF TWO-THIRDS TO WILLIAM E. PORTER AND GEORGE PENCE, OF EL PASO, TEXAS.

RAIL-JOINT CONNECTION.

SPECIFICATION forming part of Letters Patent No. 738,805, dated September 15, 1903.

Application filed February 5, 1903. Serial No. 142,000. (No model.)

To all whom it may concern:

Be it known that I, JOHN HOULEHAN, a citizen of the United States, residing at El Paso, in the county of El Paso and State of Texas, have invented a new and useful Improvement in Rail-Joint Connections, of which the following is a specification, reference being had to the accompanying drawings, forming part thereof.

10 My invention relates to a rail-joint connection for railway-rails, the object being to combine in one integral structure by forging or stamping from a single piece of metal a rail-chair and fish-plate which shall be stronger 15 and more secure than the ordinary fastening now in use.

Referring to the drawings, Figure 1 is a perspective view of my invention as it appears when in use; Fig. 2, an end view of the same, 20 and Fig. 3 a similar view of a modified form of connection.

Similar numerals of reference indicate similar parts in the respective figures.

12 represent the meeting ends of two rails, 25 and 3 my improved connection as a whole, which consists principally of a plate or strip of metal 4 bent upon itself, the under portion being placed beneath the abutting ends of the rails 1 2 and extending some distance 30 beyond on the opposite side. The upper portion of the strip 4 is formed integrally with an abutment or chair 5 and projections 6 extending laterally from the abutment, the said projections having holes for the passage there- 35 through of bolts 7. Holes are also formed in the strip 4, through which spikes are driven to fasten the rail connection 3 to a tie 8. The abutment 5 spans the adjoining ends of the rails 1 2 and extends vertically about midway 40 of the height of the rail-heads, from which point it curves gradually downwardly and away from the rails to the strip 4. The projections 6 fit snugly against the webs of the rails below the heads, as in the use of the ordinary fish-plate.

In practice the connection 3 is placed on the tie 8, the ends of the rails 1 and 2 resting on the strip 4 and the abutment 5 and pro- 45 jections 6 lying closely against the rails, as

shown in Fig. 2. A fish-plate 9 of some usual 50 or well-known form is placed against the opposite side of the rails, the whole being securely united by bolts 7 and nuts 10.

The connection illustrated in Figs. 1 and 2 is used more especially on a curve, the abut- 55 ment being placed on the outside of the outer rail on a curve to prevent the rails from spreading and to assist the outer rail to overcome the tendency to overturn due to the pressure exerted upon it by a train when 60 making the curve.

The modified construction shown in Fig. 3 is more especially designed for use on bridges. It is a practical duplication of the form seen in Figs. 1 and 2, the connection 3^a consisting 65 of the strip 4, having an abutment 5 and pro- jections 6 formed on each end, which ends are doubled over on the strip 4 to form a chair within which the rails rest. Spikes 11 pass through the doubled portion of the strip 70 4 on each side of the rail to secure the connection to the tie.

I do not restrict myself to the exact details of construction, combination, and arrangement herein set forth, it being obvious that 75 minor variations thereof not involving the exercise of invention may be made by the skilled mechanic, and such departures from what is herein described and claimed not involving invention I consider as within the 80 scope and terms of my claims.

Having thus described my invention, I claim—

1. In a rail connection, the combination of a plate or strip doubled upon itself, an abut- 85 ment on the upper portion of said doubled strip, and lateral projections on the abut- ment, substantially as set forth.

2. In a rail connection, the combination of a plate or strip doubled upon itself, an abut- 90 ment on the upper portion of said doubled strip, and lateral projections on the abut- ments, the whole being integral, substantially as set forth.

3. In a rail connection, the combination of 95 a plate or strip doubled upon itself, an abut- ment on the upper portion of said doubled strip, and lateral projections on the abutment,

the said abutment and its projections being shaped to fit the side of a rail, substantially as set forth.

4. In a rail connection, the combination of a plate or strip doubled upon itself, an abutment on the upper portion of said doubled strip, and lateral projections on the abutment, the said abutment and its projections being shaped to fit the side of a rail, the whole being integral, substantially as set forth.

5. In a rail connection, the combination of a plate or strip doubled upon itself and hav-

ing holes for spikes formed through the doubled portion, an abutment integral with said strip and shaped to fit the side of a rail, and projections on the abutment having bolt-holes therethrough for securing the connections to the rails, substantially as set forth.

In testimony whereof I hereunto set my hand and seal.

JOHN HOULEHAN. [L. S.]

In presence of—

R. W. SPENCE,
T. B. COLLIER.
